US0D1108630S

(12) **United States Design Patent** (10) **Patent No.:** **US D1,108,630 S**
(45) **Date of Patent:** **** Jan. 6, 2026**

(54) **MEDICAL DEVICE STABILIZER**

(71) Applicant: **AVACEN, INC.**, Carlsbad, CA (US)

(72) Inventors: **Michael O. Bonaguidi, Jr.**, National City, CA (US); **Melanie Klich**, Long Beach, CA (US); **Thomas Brodt**, Long Beach, CA (US); **Jorge Quintanilla**, Oxnard, CA (US); **Gregg D. Alzate**, Del Mar, CA (US)

(73) Assignee: **AVACEN, INC.**, Carlsbad, CA (US)

(**) Term: **15 Years**

(21) Appl. No.: **29/934,082**

(22) Filed: **Mar. 22, 2024**

(51) **LOC (15) Cl.** **24-02**

(52) **U.S. Cl.**

USPC **D24/128**

(58) **Field of Classification Search**

USPC D24/127-129, 186, 190, 231; D8/354,
D8/356

CPC A61B 50/20; A61B 2050/21; A61B 50/24;
A61B 50/00

(57) **CLAIM**

The ornamental design for a medical device stabilizer as shown and described.

DESCRIPTION

FIG. 1 is a perspective view of a medical device stabilizer according the disclosure;

FIG. 2 is a front view thereof;

FIG. 3 is a right view thereof;

FIG. 4 is a left view thereof;

FIG. 5 is a top view thereof;

FIG. 6 is a bottom view thereof; and,

FIG. 7 is a rear view thereof.

The broken lines in the drawings illustrate portions of the medical device stabilizer and form no part of the claimed design.

1 Claim, 7 Drawing Sheets
